2 SHEETS—SHEET 2.

UNITED STATES PATENT OFFICE.

GEORGE PERLEY MILLER, OF FOXCROFT, MAINE.

LENS-GRINDING APPARATUS.

1,406,407.

Specification of Letters Patent. Patented Feb. 14, 1922.

Application filed May 10, 1920. Serial No. 380,221.

To all whom it may concern:

Be it known that I, GEORGE P. MILLER, a citizen of the United States, residing at Foxcroft, in the county of Piscataquis and 5 State of Maine, have invented a new and useful Lens-Grinding Apparatus, of which the following is a specification.

This invention relates to apparatus for use in grinding and polishing optical lenses, 10 one of the objects of the invention being to provide a rotating lens carrying member for holding a lens in contact with a rotating lap, there being means for rotating the lens carrying member so that the lens is rotated with or against the lap and at the same 15 time given an oscillating motion whereby two curvatures can be imparted to the lens simultaneously along axes at right angles to each other, one of these curves corresponding with that of the lap while the 20 other curve corresponds with the arc of movement of the lens set up by the rotation of the lens.

A further object is to provide simple 25 means whereby the lens is free to press yieldingly against the lap so as to automatically take up wear due to the abrading action of the lap.

Another object is to provide mechanism 30 which is simple and compact, and which can be easily regulated so as to vary the arcuate movement of the lens during the grinding and polishing operation, thereby to produce variations in curvature.

35 A further object is to provide means whereby a cylindrical surface can be produced on a flat or plano lap, or on a concave or convex spherical lap because of the combined rotary and oscillating motion set up, 40 such motion being facilitated by the provision of a friction ring designed to engage the lap and to be rotated by contact therewith, thereby to insure actuation of the lens along predetermined lines.

45 With the foregoing and other objects in view, which will appear as the description proceeds, the invention resides in the combination and arrangement of parts and in the details of construction hereinafter described and claimed, it being understood that, within the scope of what is claimed, changes in the precise embodiment of the

invention shown can be made without departing from the spirit of the invention.

In the accompanying drawings the preferred forms of the invention have been shown.

In said drawings—

Figure 1 is an elevation of the grinding mechanism, the lap and the friction ring being shown in contact, said ring being in section and the lap broken away.

Figure 2 is an elevation of the lens carrying device, the casing being broken away to show the interior mechanism in elevation.

Figure 3 is a transverse section through the casing showing the interior mechanism in plan.

Figure 4 is a section on line 4—4, Figure 3.

Figure 5 is a section on line 5—5, Figure 4, the central tubular bore being shown partly in elevation.

Figure 6 is a perspective view of the rocking element.

Figure 7 is a plan view of a lens.

Figure 8 is a section on line 8—8, Figure 7.

Figure 9 is a section on line 9—9, Figure 7.

Figure 10 is a sectional through a modified form of connection between the rocker operating yoke and its drive mechanism.

Figure 11 is a section on line 11—11, Figure 10.

Figure 12 is an elevation of a special modified form of rocker operating mechanism.

Figure 13 is an elevation of another modified form of rocker operating mechanism.

Referring to the figures by characters of reference 1 designates a base plate provided with a central circular opening 2 and secured to this base plate is a bottom plate 3. The base plate 1 is cut away to provide a bottom recess 4 covered by the bottom plate

3. A diaphragm 5 of rubber or other suitable flexible material is secured at its edges to the bottom plate 3 preferably by means of a ring 6 attached to the bottom plate by screws or the like extending through the edge portion of the diaphragm. Screws 7 extend through the bottom plate and diaphragm and engage the base plate 1, these

screws being provided, at their outer ends, with balls 8 seated in sockets 9 formed within blocks 10 which are secured to a friction ring 11. By means of the screws 7 this ring can be adjusted to any desired angle relative to the base plate 1 and can be adjusted toward or from the base plate, there being openings 12 in the outer end portions of the screws 7 for the reception of pins or the like whereby the screws can be rotated readily for the purpose of securing the desired adjustment which regulates the thickness of the finished lens and also the relative thickness of the edges of the lens, thereby maintaining the desired optical center.

Secured to the base plate 1 is a cylindrical housing 13 and that face of the housing remote from the base plate 1 has a central opening 14 from the edge of which extends a circular flange 15 projecting into the housing. This flange extends into one end of a tubular core 16 the other end of which bears upon the base plate 1 and has a circular boss 17 which bears in the opening 2 and is provided with a stem 18 bearing in an opening formed in the middle portion of the bottom plate 3. A small lug 19 projects from the boss 17 and is adapted to extend into a nut formed within a gear 20 which is mounted on the stem 18 and within the recess 4, so as to rotate with the core 16, as will be obvious.

Arranged within the core 16 are spaced ears 21 and projecting loosely into the core and through the opening 14 in the housing 13 is the usual stationary spindle 22 which in the present instance, has pointed end 23 projecting into a conical seat 24 in the bottom of the core 16. An ear 25 extends radially from the stem or spindle 22 and projects between the ears 21 so that, when the housing 13 is rotated in the manner hereinafter described, the core 16 will be held against rotation by the stem 22 although capable of rocking relative thereto.

Secured upon the base plate 1 is a bearing frame 26 in which is journaled the upper end of a shaft 27 the lower end of which is journaled in the bottom plate 3 and carries a gear 28 which constantly meshes with the gear 20. Another gear 29 is secured to the shaft 27 and projects through an opening 30 in the base plate 1, this gear 29 in turn meshing with a gear 31 secured to another shaft 32. Shaft 32 is journaled at its lower end in the base plate 1 and at its upper end in the bracket 26 and has a disk 33 secured to the upper portion thereof and bearing downwardly on the bracket 26. A dove-tailed groove 34 extends diametrically across the face of the disk 33 and slidably mounted in this groove is a block 35 carrying a set screw 36 to which access may be had by removing a closure 37 connected to the housing 13. This set screw 36 has an

enlarged cylindrical portion 38 which bears downwardly on a washer 39 bridging the dove-tailed groove 34 so that when the set screw is tightened the block 35 and washer 39 will cooperate to bind upon the disk 33 so as to hold the block 35 against movement along the groove 34.

Bearing arms 40 extend from the sides of the bracket 26 and constitute side abutments for fingers 41 projecting from a yoke 42. A rod 43 connects these fingers and is slidably engaged by a block 44 in which the cylindrical portion 38 of the set screw 36 is adapted to rotate, thus to form a wrist pin. The free ends of the yoke 42 carry rollers 45 which are mounted for travel along cam tracks 46 formed by the upper edges of brackets 47 secured to the base plate 1. These rollers are also connected to the upstanding arms 48 and 49 of a rocker such as shown in Figure 6, these arms being arranged at diametrically opposed portions of a plate 50 and one of the arms, 48, terminating in an index or point 51. The arms 48 and 49 extend loosely through slots 52 formed in the base plate 1 and the bottom plate 3 and the disk or plate 50 is thus supported outside of the housing 13 and is concealed between the diaphragm 5 and the bottom plate 3 as shown particularly in Figure 5. A disk 53 is arranged on the outer face of the diaphragm 5 and has a central threaded opening 54. This disk is secured to the disk or plate 50 by rivets or the like extending through the diaphragm 5 and the opening 54 is adapted to receive a threaded stem 55 extending from a disk 56 to which a lens indicated at L is adapted to be cemented.

Formed in the plate 50 at diametrically opposed points are conical depressions 50' and projecting into these depressions are the pointed ends 57 of rods 58 which slide within the base plate 1 and also within sockets 59 formed in the top of the housing 13. Springs 60 are mounted on the rods and bear against collars 61 carried by the rods. Thus these springs serve to hold the rods normally pressed against the disk or plate 50 and to maintain the rollers 45 normally in contact with the cam tracks 46.

The index or point 51 projects through a slot 62 in the housing and is adapted to work along a dial 63 arranged within a housing 64. This dial is designed to indicate in degrees the extent of rocking movement set up when the disk 33 is rotated in the manner hereinafter described.

As heretofore pointed out the mechanism herein-described is designed for use in producing either plano or toric cylindrical surfaces from a plano or spherical lap. The glass disk to be shaped into a lens is cemented to the disk 56 which, in turn, is attached to the disk 53. This glass disk will thus be supported within the opening in the

ring 11 and will project beyond the flat, convex or concave face of the ring. Said ring is shaped to conform with the curvature of the lap shown at 65 and which is driven in the usual manner. The lens is applied to the lap at a point off center as shown, for example, in Figure 1, and as the stem or spindle 32 is held against rotation, it will be obvious that as the lap rotates it will drag upon the ring 11 and cause said ring to rotate therewith, the lap, at the same time, grinding the exposed face of the glass disk L because the center of rotation of the lap is not in line with the center of rotation of the disk although said disk is being rotated because of the frictional contact thereof and of the ring 11 with the lap. As the stem 22 cannot rotate, the rotation of the ring 11 and, consequently, the rotation of the housing 13 to which the ring is attached, will result in the gear 28 rotating about the held gear 20. Thus motion will be transmitted through the shaft 27 and gears 29 and 31 to the shaft 32 with the result that the disk 33 will be revolved and will cause the wrist pin 38 to impart a back and forth motion or reciprocation to the yoke 42. As the yoke reciprocates the rollers will travel along the cam rails 46 and cause the arms 48 and 49 and the plate 50 to rock with the points 57 as fulcrums. The springs 60 will of course press the lens firmly against the lap so as to take up wear. The diaphragm 5 prevents the carborundum or other abrasive material used from working up into the housing 13 and injuring the mechanism.

The curvature of the rails 46 regulates the curvature of the lens produced by the oscillating movement and where a different curvature is to be used different brackets 47 can be employed. Likewise by shifting the block 35 diametrically relative to the disk 33, the extent of rocking movement can be varied and this, likewise, will regulate the curves produced by the oscillation. Instead of having rollers mounted on cam tracks, the yoke 42 can be connected to cams 66 adapted to travel upon straight tracks 67 as shown in Figure 12, or, if preferred, the yoke 42 can be attached to the ends of rockers 68 adapted to bear and rock upon the base plate 1 as shown in Figure 13.

Also, if preferred, instead of utilizing the wrist pin or set screw 36 for the purpose of securing the block 35 in adjusted position, the block, indicated at 69 in Figure 10 can have a lug or ear 70 engaged by an adjusting screw 71 swiveled at the ends of the dove-tailed groove 72 so that, by the insertion of a tool of suitable shape, the screw 71 can be rotated and the block 69 shifted longitudinally. With this arrangement it is only necessary to provide an ordinary wrist pin upon the block 69 for engaging the part 44.

What is claimed is:

1. In lens grinding mechanism, a ring for engagement with a lap during the application of the lens to a lap, and a lens oscillating or rocking device including means operated by the ring for rocking said device relative to the ring. 70

2. In lens grinding mechanism, a ring for engagement with the rotating lap, a lens oscillating or rocking device including means actuated by the rotation of the ring for oscillating said device relative to the ring, and yielding means for pressing said device toward the lap during the rotation of the lap. 75

3. Lens grinding apparatus for use on a rotating lap, said apparatus including means for engaging a lens, a ring for engaging the lap off center so as to be driven by the lap, mechanism operated by the ring 85 during its rotation, for rocking said lens engaging means relative to the lap, and yielding means for pressing the lens engaging means toward the lap.

4. Lens grinding apparatus including a nonrevolvable spindle, a housing tiltable and revolvable relative to the spindle, means movably carried by the housing for engaging a lens, a ring connected to and revolvable with the housing for engagement with a lap to rotate the housing, and means operated by the rotation of the housing relative to the spindle for imparting a rocking movement to the movable lens engaging means transversely of the axis of rotation of the 100 housing. 90

5. Lens grinding apparatus including a ring for engagement with a rotating lap for actuation thereby, a stationary spindle, said ring being shiftable angularly relative to the 105 spindle, means for engaging a lens and supporting it within the ring, and means operated by the rotation of the ring relative to the spindle for imparting a rocking movement to the lens engaging means transversely 110 of the axis of rotation of the ring. 110

6. Apparatus for grinding toric and cylindrical surfaces on a rotating lap, comprising means for engaging and supporting a lens, means engaging and actuated by the lap for rotating the lens supporting means, and adjustable means operated by the lens support rotating means for rocking said lens supporting means across the axis of rotation of the lap. 115

7. Mechanism for grinding toric and cylindrical surfaces on a rotating lap, comprising a non-revolving spindle, a housing mounted to tilt relative to and to rotate about the spindle, means connected to the 125 housing for engagement with and actuation by the lap to rotate the housing, lens supporting means rotatable with the housing, means operated by the rotation of the housing relative to the spindle for rocking said 130

- lens supporting means transversely of the axis of rotation of the housing, and yielding means for pressing the lens supporting means toward the lap to take up wear upon the lens.
8. Lens grinding mechanism for use in connection with a rotating lap, comprising a non-revolving spindle, a housing mounted for rotation relative to the spindle, means carried by the housing for engagement with and actuation by the lap to rotate the housing, lens engaging means revoluble with the housing, adjustable means in the housing and operated by the rotation of the housing relative to the spindle for oscillating the lens engaging means transversely of the axis of rotation of the housing.
9. Lens grinding apparatus for engagement with and actuation by a rotating lap, comprising a stationary spindle, a housing mounted for rotation relative thereto and tilttable relative to the spindle, means movably connected to but revoluble with the housing for attachment to a lens, means revoluble with the housing for engagement with a lap to rotate the housing, when said housing is tilted to any angle relative to the spindle, and means operated by the rotation of the housing relative to the spindle for rocking the lens engaging means across the axis of rotation of the lap.
10. In lens grinding mechanism for use with a rotatable lap, the combination with a housing mounted for rotation and tilttable relative to the lap and stationary means projecting into and tilttable with the housing but held against rotation therewith, of a ring secured to and rotatable with the housing for engagement with and actuation by the lap to rotate the housing, means tiltably connected to the housing for attachment to a lens to support the lens within the ring in position for contact with the lap, and means operated by the rotation of the housing relative to the stationary means therein for rocking said tilttable lens carrying means.
11. Lens grinding apparatus for use in connection with a rotatable lap, comprising a rotatable housing tilttable relative to the axis of rotation of the lap, a stationary element projecting into the housing, a ring connected to the housing for engagement with and actuation by the lap to rotate the housing, means yieldingly connected to and rotatable with the housing for supporting a lens within the ring, flexible sealing means connecting said lens supporting means to the housing, and adjustable means operated by the rotation of the housing relative to said stationary element for rocking the lens relative to the housing and to the lap during the rotation of the housing.
12. Lens grinding apparatus for use with a rotatable lap, comprising a housing mounted for rotation and tilttable relative to the axis of rotation of the lap, a nonrotatable element projecting into the housing, a lap engaging ring adjustably connected to and revoluble with the housing, a plate outside of the housing, arms extending therefrom and into the housing, cams within the housing for supporting the arms, spring pressed means engaging the plate for holding it yieldingly pressed away from the housing, means detachably connected to the plate for attachment to a lens and for supporting the lens within the ring, a yoke connected to the arms, adjustable means operated by the rotation of the housing relative to the nonrotatable element therein for actuating the yoke to oscillate the arms relative to the housing.

In testimony that I claim the foregoing as my own, I have hereto affixed my signature in the presence of two witnesses.

GEORGE PERLEY MILLER.
